CHARCOAL BURNING GRILL

Lorence O'Russo, 5309 Prospect, Peoria, Ill.

Filed Nov. 13, 1964, Ser. No. 82,586

Term of patent 14 years

(Cl. D81—10)

FIG. 1 is a front elevational view of a charcoal burning grill, showing my new design;

FIG. 2 is a side elevational view thereof; and

FIG. 3 is a top plan view thereof.

I claim:

The ornamental design for a charcoal burning grill, as shown.
